CLAIM

The design for packaging for batteries, as shown and described.

DESCRIPTION

FIG. 1 is a top perspective view of a packaging for batteries showing our new ornamental design.

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines shown represent unclaimed subject matter and form no part of the claimed design.

The claim is shown with a symbolic break in its width. The appearance of any portion of the article between the break lines forms no part of the claimed design.

The figures are lined for the colors black and copper, wherein black is represented by a solid fill and copper is represented by cross-hatching.
